(57) **CLAIM**

The ornamental design for a replaceable cartridge for a dental syringe, as shown and described.

DESCRIPTION

FIG. 1 is a perspective view of a replaceable cartridge for a dental syringe according to our new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an exploded left side elevation view thereof shown in the environment of a dental syringe.

Broken lines shown herein for illustrative purposes or which define the bounds of the claimed design form no part of the claimed design. The broken lines of FIGS. 1–8 define bounds and form no part of the claimed design. The broken lines of the dental syringe of FIG. 9 illustrate environmental structure and form no part of the claimed design.
